CANE CONSTRUCTION

Original Filed June 29, 1929

Inventor
A. Soriente

By his Attorney J. Ledermann

UNITED STATES PATENT OFFICE

ALFONSO SORIENTE, OF BROOKLYN, NEW YORK

CANE CONSTRUCTION

Application filed June 29, 1929, Serial No. 374,892. Renewed October 20, 1930.

The main object of this invention is to provide a novel type of cane construction in which small longitudinal elements of diversely colored wood are glued together and 5 then turned in such manner that a cane of ingenious ornamentation is produced.

Another object of this invention is to provide a cane formed of blocks of variously colored wood glued together to provide a 10 longitudinal element which is channeled longitudinally to provide reinforcing strips. The blocks may be mitered or squared according to the design desired.

The above and other objects will become 15 apparent in the description below, in which characters of reference refer to like-named parts in the drawing.

Referring briefly to the drawing, Figure 1 is a longitudinal elevational view of the cane, 20 showing the same with one form of block.

Figure 2 is a longitudinal elevational view of another type of cane, showing the use of squared blocks.

Figure 3 is an enlarged cross sectional view 25 taken on line 3—3 of Figure 1.

Figure 4 is an enlarged cross sectional view taken on line 4—4 of Figure 2.

Figure 5 is a section of cane showing still another modified form of block.

Referring in detail to the drawing, the 30 numeral 10 indicates the handle of one form of cane. To prevent the easy fracture of this crooked handle 10 a reinforcing strip 11 is imbedded in a channel in the handle 10 and 35 roughly follows the shape of the handle 10 and also aids in the ornamentation thereof, as this strip 11 is of a color different from that of the body of the handle 10. The cane may also be provided with a ball handle such as 40 that indicated by the numeral 25 which is just as readily attached, its application being merely a matter of choice.

The cane construction for different ornamental types of canes follows the same process in the course of manufacture. Four blocks, of alternately colored wood, indicated by the numerals 12, 13, 14, and 15 are used 45 in the process of construction. These blocks 12, 13, 14 and 15 have two right-angled faces 50 16 and 17, and these faces 16 and 17 are glued

to faces of adjacent blocks. Said blocks are arranged end to end in parallel rows in alternate colors. In one form of cane, illustrated in Figure 2, the one block overlaps the block opposite to it, as indicated by the stepped formation of the blocks, 18 and 19. The faces 55 16 and 17 which lie in contact with each other are divided by channels which are formed after the blocks 12, 13, 14 and 15 have been glued into a longitudinal stick-like member, and these channels receive reinforcing strips 20 of variously colored wood.

The cane illustrated in Figure 1 is provided with eight strips 20 which extend longitudinally the entire length of the cane from the 60 tip 21 to the handle 10.

Figure 2 shows a cane provided with a trio of strips 22 which are alternately different in color and are let into a substantially larger channel. These strips reinforce the cane 70 lengthwise and prevent the blocks from becoming detached from each other under the influence of the changes of temperature. The cross section of the cane which is illustrated on the drawing at any position along its 75 length shows four blocks 12, 13, 14 and 15 which are glued to each other in a substantial manner, but may be mitered and squared into various shapes as illustrated by the blocks 23 shown in Figure 5 in which the blocks 23 have 80 spiral aprons. In Figure 1 the same blocks 24 have an endlike appearance, while the blocks 18 and 19 show an overlapped and staggered relation to each other in Figure 2.

It is to be noted that certain changes in 85 form and construction may be made without departing from the spirit and scope of the invention.

I claim:

1. In a cane, a plurality of blocks arranged end to end in overlapped relation to each other for forming the staff of a cane, said blocks being alternately different in color and different in color at random, and strips 90 forming part of said cane for reinforcing said staff.
2. In a cane, a plurality of blocks arranged end to end, the cross section of said cane being composed of four blocks alternately colored, 100

strips joining said blocks for reinforcing the cane.

3. In a cane, a plurality of blocks arranged end to end, the cross section of said cane being composed of four blocks alternately colored, said blocks having channels therein arranged lengthwise after the staff of said cane is formed, said channels receiving strips alternately colored for reinforcing said formed staff.

10 In testimony whereof I affix my signature.
ALFONSO SORIENTE.
